CROWN BLOCK

Application filed July 7, 1926. Serial No. 120,971.

This invention has relation to crown blocks utilized on derrick structures for guiding cable lines in the drilling of oil wells and other operations incidental thereto.

5 In the standard form of crown blocks now generally employed in oil well drilling operations it has been the practice to arrange the sheaves in such relation to each other that the pull of the various cable lines shall 10 be as nearly vertical as possible in order to lessen the wear on the lines and sheaves during hoisting and lowering operations. In order to attain such results it has been customary to arrange some of the sheave bearings so that they may be adjusted transversely in the crown block, and as a consequence the diameter of the sheaves in such cases must be reduced to a minimum to allow room for adjustment. Further, as the sheaves are 15 disposed in the same direction it is impossible to bring the same close enough to line up with the sheaves of the travelling block, and as a result cause an untrue "tracking" of the cable lines with resultant wear on the lines and 20 sheave flanges. It has also been the purpose to arrange the sheaves, whereby sheaves of large diameter may be used to minimize the stresses imposed upon the lines by the smaller 25 diameter sheaves.

30 It is therefore a main object of the present invention to provide a crown block construction in which the diameter of sheaves employed are proportionate to the diameter of the cable lines used therewith, whereby to 35 greatly lessen the wear of the lines due to "bending friction".

Another object is to provide an arrangement of sheaves in which the starting lines from the "bull and calf" draw works wheels 40 will uniformly spool, thereby rendering it unnecessary to move or "skid" the crown block at the derrick top, or to move the equipment on the derrick floor to correspond.

Another object is to provide an arrangement of the crown block sheaves in which the cable lines will "track" from one sheave to another, thereby eliminating side friction in the lines during their operation.

A further and important object is to increase the diameter of the sheaves over which

the fast moving lines operate, and to decrease the diameter of the sheaves over which the slow moving lines operate, in order to eliminate frictional heat generated by bending strains.

Still another object is to arrange the various line sheaves that the lines leading therefrom may be "fanned" in the desired direction without destroying the line-up or tracking of the pulley sheave grooves.

In the disposition of the sheaves of the present invention the cable lines leading therefrom to the "travelling block" will be so directed thereto that the block will at all times during its operation maintain a substantially vertical position, thereby obviating undue wear on the lines, and preventing accidental displacement of the derrick "fingerboard" and other structures.

The above and other objects are attained by the construction described herein, and illustrated in the accompanying drawings, in which:

Fig. 1 is a side elevation of the upper end of a well derrick showing the lines from the crown block sheaves leading to the travelling block.

Fig. 2 is an end elevation of the above.

Fig. 3 is a plan view of the crown block.

Fig. 4 is a diagrammatic view illustrating a complete threading of the various cable lines with respect to the crown and travelling blocks and the derrick equipment.

Fig. 5 is a view similar to the above showing the "threading" of the crown block when only three of the travelling block sheaves are used.

Fig. 6 is another similar view showing the method of threading the crown block when only two of the travelling block sheaves are used.

The present invention contemplates a novel arrangement of crown block sheaves (here shown as seven) in which the sheaves of greatest diameter and over which pass the fast moving cable lines are all disposed over and at right angles to the smaller casing, sand and spudding sheaves over which pass the slow moving lines.

Referring now more particularly to the drawings, 10 designates the upright derrick timbers, four in number connected together at their upper ends with cross timbers 11. Oppositely disposed on a pair of the cross timbers 11 are similar cross timbers 12, all bolted together to form a rigid structure. Disposed on top of timbers 12 are a plurality of channel beams arranged in pairs 13, 14, 15, 16 in parallel rows and suitably secured to the cross beams 12 by which they are supported.

Mounted in bearings 17, 18, between the oppositely disposed channels of beam pairs, 15 13, 14 and 15, 16, are a pair of casing sheaves 19, 20, of relatively small diameter utilized when handling well casing. Secured in a strap bearing 21 bolted to a pair of brackets 22 disposed on the upper flanges of the oppositely disposed channel members of the pairs of beams 14, 15, is a spudding sheave 23 over which passes the spudding line 24 from the "bull" wheel 25 located on the derrick floor. Mounted in bearings 27, secured to the top flanges of the oppositely disposed beams of the beam pairs 14, 15 is a sand line sheave 28, over which passes the cable line 29 from the sand reel 30.

Disposed upon the pairs of channel beams 30 13, 14, 15 and 16 and extending in the same direction are I-beams 31, 32, 33 and 34, that in turn support a pair of channel beams 35 that extend transversely from beam 31 to beam 34, (see Fig. 2). Mounted on and secured to the uppermost flanges of beams 35, and midway of their ends are a pair of oppositely disposed vertically extending bearings 36 designed to support a plurality of downwardly extending strap plates 37 between which are mounted in bearings (not shown) the three fast moving casing sheaves of the greatest diameter 39, 40, and 41, the operating cable lines passing thereover and downwardly around the sheaves of the travelling block, the bearings in the strap plates for the casing sheave pins being arranged in staggered relation.

It will be noted that the three last mentioned sheaves are disposed at substantially 50 right angles to the sheaves disposed therebelow, sheave 40, being directly over the center of the well with the two others 39, 41, at each side. By this arrangement the fastest moving cable lines are operated directly over the center of the well, and as the sheaves are of 55 large diameter the excess of frictional heat generated by bending strains is largely obviated. This feature of the "crown block construction" is considered one of the most important features of the invention, as by such an arrangement of the various sheaves the starting lines from the draw works and the 60 calf wheel will uniformly spool, and the lines leading from the sheaves to the travelling block will maintain said block in nearly ver-

tical position, which position is considered highly essential in drilling operations.

In the diagram illustrated in Fig. 4 five of the crown block sheaves are in operation, and the method of "threading" is as follows: From 70 the draw works 50 the main operating cable 42, passes upwardly and around crown sheave 41, thence downwardly to sheave 51 of the travelling block and then upwardly over crown sheave 40, downwardly to sheave 52 of 75 the block, again upwardly and over crown sheave 39 and then downwardly to sheave 53 of the block, upwardly to crown sheave 20 then downwardly to sheave 55 of the block, upwardly to crown sheave 19, and thence 80 downwardly where it is made fast to the calf wheel 43.

It frequently happens that when the drilling tools, pipe casings, and like structures to be lifted are not excessively heavy, that some 85 of the sheaves in the crown block may be dispensed with, and in Fig. 5 is shown the method of threading the cable lines when only four sheaves are employed. The cable line 42 from the draw works 50, passes upwardly and over 90 crown sheave 40, downwardly to sheave 52 of the travelling block, thence upwardly and over crown sheave 39, downwardly and around sheave 53 upwardly and over crown sheave 20, downwardly and around sheave 95 55, upwardly and over crown sheave 19, and finally downwardly to the calf wheel 43.

When lifting comparatively light objects only two sheaves of the crown block are generally employed, and in Fig. 6 is shown 100 diagrammatically the threading arrangement in such cases.

The main operating cable line 42 from the draw works 50 passes upwardly and around sheave 39, downwardly to block sheave 53, 105 upwardly and over sheave 20, downwardly and around block sheave 55, upwardly over sheave 19, and thence to the calf wheel.

The sand reel line 29 passes in each instance from the reel 30, upwardly and over sand sheave 28, while the "bull" wheel line 24 passes upwardly from the "bull" wheel 25 around the "crown sheave" 23. The sand reel line is utilized during drilling for operating the bailer or other light hoisting from the derrick floor. The bull wheel line is so arranged that its free end is disposed directly over the center of the derrick.

It will be apparent from the above arrangement of the various sheaves of the crown block, the cable lines will lead on and off practically straight with the sheave grooves, without imposing side pressure on the groove flanges, or creating any appreciable stress upon the cables due to bending friction. 120 Further, by the arrangement of the sheaves one set above another it will be possible to condense the same so that the lines therefrom will lead in a more nearly vertical direction to the travelling block. Also by arranging the fast 130

moving sheaves at an angle to the slow moving ones and above the same, sheaves of larger diameter may be employed, and in consequence the cable lines leading to the travelling block will maintain the same in a substantially vertical position.

While the face width of the grouped crown block sheaves are illustrated as smaller than the face width of the traveling block sheaves, 10 it will be understood that I do not wish to be limited to the exact proportional relation of said sheaves, as the face width of the grouped crown block sheaves may be formed equal to the face width of the sheaves of the 15 traveling block without substantially altering or affecting the directional movement of the cable lines.

What I claim is:

1. The combination with a traveling block, 20 of a crown block construction comprising two groups of cable sheaves disposed one above the other, the extreme face width of one group being approximately equal to the face width of the sheaves of the traveling 25 block, the extreme face width of the other group of sheaves being approximately equal to the diametrical dimension of the sheaves of the traveling block, whereby the cable lines leading from the crown block sheaves 30 to the sheaves of the traveling block will enter and leave the grooves of the traveling block sheaves at a minimum angle from the vertical.

2. A crown block construction for oil well 35 derricks comprising a plurality of supporting frames for cable sheaves, said frames being disposed one above another and secured in rigid relation to each other, grouped shafts for mounting casing sheaves for carrying slow moving cable lines mounted in 40 bearings on the lower frame, said shafts being disposed in parallel relation, and a plurality of centrally disposed grouped shafts mounted in bearings on the upper frame at 45 right angles to the shafts in the frames therebelow for mounting relatively large casing sheaves for engaging fast moving casing lines, the extreme face width of each shaft group being substantially equal to the face 50 width or diameter of the traveling block sheaves suspended by the cable lines leading from the same.

3. A crown block construction for oil well 55 derricks comprising a plurality of horizontally disposed metal frames bolted together one above another, a pair of casing sheaves mounted in bearings on the lower frame, said sheaves being adapted to engage the slow moving casing sheave lines, and a group of 60 sheaves disposed on shafts mounted in bearings on the uppermost frame, said sheaves being disposed at right angles to the pair of sheaves disposed directly therebelow, the extreme face width of each group being substantially 65 equal to the face width or diameter

of the traveling block sheaves suspended by the cable lines leading from the crown block, whereby the cable lines will be directed to the sheaves of the traveling block in a vertical direction and in approximate parallel relation.

4. A crown block construction for oil well derricks comprising a plurality of frame members secured together one above another, a shaft for mounting a spudding sheave and a shaft for mounting a sand line sheave disposed in bearings on the lowermost frame, shafts for mounting casing sheaves carrying slow moving lines disposed on the upper frame, a sheave on either side of the sand line and spudding line sheaves, said shafts being disposed in parallel relation to the spudding and sand line sheaves, and a plurality of centrally disposed shafts mounted in bearings on the uppermost frame at right angles to the shafts in the frames therebelow for mounting casing sheaves adapted to be engaged by fast moving lines, the face width of the various grouped sets of casing sheaves being substantially equal to the face width or 90 diameter of the traveling block sheaves located below the crown block, the sheaves of which the various cable lines engage, whereby the groups of casing cable lines will be directed to the sheaves of the traveling block 95 in a substantially vertical direction and in approximately parallel relation.

5. A crown block construction for oil well derricks comprising a plurality of frames disposed one above another and bolted to each 100 other to form a rigid structure, a shaft for mounting a spudding sheave and a shaft for mounting a sand line sheave mounted on the lowermost frame, shafts for mounting casing sheaves adapted to carry slow moving 105 cable lines mounted in bearings on the lower frame, one on each side of the sand line and spudding line sheaves, said sheaves being disposed in parallel relation to the sand and spudding line sheaves, a plurality of strap plate bearings centrally disposed on the uppermost frame and rigidly secured thereto, and a plurality of sheaves for carrying fast 110 moving casing lines each provided with trunnions engaging the strap plate bearings, said 115 sheaves being disposed at right angles to the sheaves in the frames therebelow.

6. The combination with a traveling block, of a crown block construction comprising two groups of cable sheaves disposed one 120 above the other and at approximately right angles to each other, the extreme face width of one group being approximately equal to the face width of the sheaves of the traveling block, while the extreme face width of the other group is approximately equal to the diametrical dimensions of the sheaves of the traveling block, whereby the cable lines leading from the groups of sheaves of the crown block to the sheaves of the traveling block 125 130

will enter and leave the grooves of the traveling block sheaves at a minimum angle from the vertical.

In witness that I claim the foregoing I
5 have hereunto subscribed my name this 9th day of June, 1926.

BURT STANLEY MINOR.
